HEATING UNIT

William Toomey, Edgewood, Pa.

Application August 19, 1941, Serial No. 407,465

4 Claims. (Cl. 126—73)

This invention relates to a heating unit, and it is an object of the invention to provide a device of this kind which requires no grate.

Another object of the invention is to provide a device of this kind wherein the fire bed is supported by the ashes, and wherein the fire chamber is provided at vertically spaced points with draft inlet openings.

The invention consists in the details of construction and in the combination and arrangement of the several parts of my improved heating unit whereby certain important advantages are attained, as will be hereinafter more fully set forth.

In order that my invention may be the better understood, I will now proceed to describe the same with reference to the accompanying drawing, wherein—

Figure 1 is a vertical sectional view of a heating unit constructed in accordance with an embodiment of my invention, with a portion in elevation; and

Figure 2 is a sectional view taken substantially on the line 2—2 of Figure 1.

My invention as herein embodied is disclosed as of a pipeless furnace type, although it is believed to be obvious that the casing can be made of a type to allow the same to be used with heating pipes or, if preferred, the casing can be in the nature of a boiler to allow either the use of steam or hot water.

In the present embodiment of my invention B denotes a base structure preferably of brick, and which is constructed in its top portion to provide an ash pit 1 opening through a side of the base B. Positioned upon the base B and extending across the outer or free end portion of the pit 1 is an annular bottom plate 2 provided with the suitably spaced and upstanding concentric flanges 3. These flanges 3 are spaced inwardly from the edges of the plate 2 to allow for the proper mounting on said plate 2 of the casing 4 and the central elongated tubular member 5. This member 5 is open at both ends and as herein disclosed is of the same internal diameter throughout its length. The lower portion of this member 5 constitutes the fire chamber, while the upper portion constitutes the combustion chamber. Fitted upon the upper portion of the member 5 is a flue 6 and, as herein disclosed, this flue 6 extends out through the side wall of the casing 7 for communication with a suitable chimney or otherwise as may be preferred.

The member 5 is of a transverse diameter considerably less than the corresponding diameter of

the casing 7. The member 5 is also considerably shorter in length than the casing 7 so that this member 5 has its upper end terminating a material distance below the upper end of the casing 7. As illustrated in the accompanying drawing, the upper end portion of the casing 7 has a constricted portion 8 terminating in an upstanding duct 9 for close contact from below with the floor F of a building structure. Disposed over this duct 9 is a conventional register or grid 10.

The upper portion of the member 5 is provided in its wall with a fuel opening 11. This opening 11 is defined by an outstanding hopper 12 which is disposed outwardly through the adjacent portion of the side wall of the casing 7. This extended portion of the hopper 12 is provided at its top with a swinging door 14 to allow the desired fueling of the unit. The lower portion of the casing 7 is provided with an air inlet opening 15 over which is disposed a suitable screening element 16.

The member 5, at substantially diametrically opposed points, is provided exteriorly thereof and spaced therefrom with the breather pipes 17 and 18, the extremities of which being in communication, as at 19, with the member 5. As illustrated in Figure 2 of the drawing, the pipes 17 and 18 throughout their major portions are spaced from the member 5 and the pipe 18 is of a length less than the length of the pipe 17, and positioned centrally with respect thereto. The lower end portion of the pipe 17 is provided with a tubular member or sleeve 20 extending through the wall of the casing 7 and threading in this sleeve 20 is a plug damper 21 for controlling the flow through the breather pipe 17. This plug damper 21 has fixed thereto a stem 22 which extends out through the head 23 for the sleeve 20. The outer or extended end of this stem 22 carries an operating member 24 whereby the plug damper can be manually rotated as desired.

The member 5 in its lower portion is provided with draft openings 25 each of which having in communication therewith a vent 26 extending out through the adjacent portion of the wall of the casing 7 with the outer ends of the vents 26 continued by the depending nipples 27.

In practice, the fire is first ignited in the ash pit 1 and in the adjacent lower portion or fire chamber of the member 5. Initially the desired draft for the support of combustion will enter the member 5 through the open end of the ash pit 1. As the ashes rise within the member 5 so will the ash pit, and as the fire bed raises the desired air for supporting combustion will

enter through the openings 25. After the fire bed has raised any considerable distance within the member 5 it is only required to pull out the ashes within the pit 1, whereupon the fire bed will drop in accordance with the amount of such ashes removed. The heating action of the member 5 with respect to the air within the casing 7 is materially increased through the medium of the breather pipes 17 and 18. The flow through the breather pipe 17 may be readily regulated by proper manipulation of the damper plug 21.

From the foregoing description is thought to be obvious that a heating unit constructed in accordance with my invention is particularly well adapted for use by reason of the convenience and facility with which it may be assembled and operated.

I claim:

1. A heating unit comprising a base having an ash pit, an upstanding tubular member mounted on the base and disposed over the ash pit, the upper portion of the tubular member being provided with a fuel opening and the lower portion of the tubular member being provided with vertically spaced air openings for the support of combustion within the tubular member, and breather pipes positioned exteriorly of the tubular member and extending lengthwise thereof, said breather pipes being substantially diametrically opposed and in communication with the tubular member, one of said breather pipes being of a length less than the opposed breather pipe and positioned centrally with respect thereto.

2. A heating unit comprising a base having an ash pit, an upstanding tubular member mounted on the base and disposed over the ash pit, the upper portion of the tubular member being provided with a fuel opening and the lower portion of the tubular member being provided with vertically spaced air openings for the support of combustion within the tubular member, breather pipes positioned exteriorly of the tubular member and extending lengthwise thereof, said

breather pipes being substantially diametrically opposed and in communication with the tubular member, one of said breather pipes being of a length less than the opposed breather pipe and positioned centrally with respect thereto, and a damper for controlling the flow through one of the breather pipes.

3. A heating unit comprising a base having an ash pit, an upstanding tubular member mounted on the base and disposed over the ash pit, the upper portion of the tubular member being provided with a fuel opening and the lower portion of the tubular member being provided with vertically spaced air openings for the support of combustion within the tubular member, breather pipes positioned exteriorly of the tubular member and extending lengthwise thereof, said breather pipes being substantially diametrically opposed and in communication with the tubular member, one of said breather pipes being of a length less than the opposed breather pipe and positioned centrally with respect thereto, and a damper for controlling the flow through the longer breather pipe.

4. A heating unit comprising a base having an ash pit, an upstanding tubular member mounted on the base and disposed over the ash pit, the upper portion of the tubular member being provided with a fuel opening and the lower portion of the tubular member being provided with vertically spaced air openings for the support of combustion within the tubular member, breather pipes positioned exteriorly of the tubular member and extending lengthwise thereof, said breather pipes being substantially diametrically opposed and in communication with the tubular member, one of said breather pipes being of a length less than the opposed breather pipe and positioned centrally with respect thereto; a casing surrounding the upstanding tubular member, a sleeve extending through the casing and in communication with one of the breather pipes, and a damper working in said sleeve for controlling the flow through such breather pipe.

WILLIAM TOOMEY.
